COMPRESSION RIVETER

Frithiof P. Forss, Aurora, Ill., assignor to Independent Pneumatic Tool Company, Chicago, Ill., a corporation of Delaware

Application November 27, 1939, Serial No. 306,254

12 Claims. (Cl. 78—48)

This invention relates to riveting machines and more particularly to riveting machines of the compression type.

The invention is concerned with compression riveters of the portable character and has for its principal object the provision of a power generating mechanism which enables a relatively small and compact hand manipulated riveter to develop considerable power as required for cold riveting in metal airplane production and kindred work.

In accordance with my invention, the power generating mechanism referred to may take the form of a combined cam and lever action carried by the machine between its power applying and riveting elements, respectively. The cam is shaped and disposed to gradually diminish the unit of arcuate movement of the lever in the power stroke of the machine and thus greatly increase the power of the lever on the riveting element. This increase of power is sufficient to head and clamp a rivet on each power stroke of the machine, thus adapting the machine for production work.

A further object of my invention is to provide a cam which gives a relatively fast travel to the lever in its initial movement on a power stroke so as to quickly bring the riveting plunger into contact with the rivet.

A further object of my invention is to provide a novel form of throttle valve mechanism for controlling the admission and exhaust of pressure fluid to and from the cylinders of the machine, said valve being so constructed that a spring pressure must be overcome by the operator to avoid sudden starting of the machine.

A further object of my invention is to provide an adjustable stop to regulate the travel of the plunger and thus adapt the machine for long and shorter rivets.

A further object of my invention is to provide a relief valve for controlling the applied pressure on the machine, and thus make the machine usable for rivets of different ductilities.

The invention consists further in the features hereinafter described and claimed.

In the accompanying drawings—

Fig. 1 is a longitudinal sectional view with parts in elevation of the compression riveting machine constructed in accordance with my invention;

Fig. 2 is a similar view taken on line 2—2 of Fig. 1;

Fig. 3 is a cross sectional view with parts in elevation taken on line 3—3 of Fig. 1;

Fig. 4 is a fragmentary longitudinal sectional view with parts in elevation taken on line 4—4 of Fig. 1;

Fig. 5 is a similar view showing the mounting for the plunger in its released position;

Fig. 6 is an end view of the parts shown in Fig. 4;

Fig. 7 is a fragmentary top plan view of a stop element to be later described;

Fig. 8 is a side view of the housing which mounts the riveting plunger;

Fig. 9 is a similar view of one of the keybars to be later described;

Fig. 10 is a longitudinal sectional view with parts in elevation of the throttle valve, the latter being shown in a position to supply pressure fluid to the main cylinder;

Fig. 11 is a similar view of said valve, the latter being shown in a position to supply pressure fluid to the auxiliary cylinder;

Fig. 12 is a view similar to Fig. 4 showing the stop adjusted to limit the stroke of the riveting plunger; and

Figs. 13, 14 and 15 are diagrammatic views showing the action of the power mechanism and the throttle valve, respectively.

The machine shown in the drawings is designed to head cold rivets of alloy steel or Duralumin, which rivets are used in the building of metal airplanes and require considerable power to clamp the metal sheets or plates together and form a proper head on the rivets. The machine shown is portable, being relatively light in weight and compact and small in size for convenience in manipulation and holding in the hands of an operator.

The machine illustrated comprises a frame or support 1 to one end of which is secured a main power cylinder 2 and to the other end of which frame is secured a yoke element 3 having an anvil 4 in line with a riveting plunger or ram 5. The latter is reciprocably mounted in the support 1 and is projected forwardly for heading a rivet and securely clamping the riveted plates together by a combined lever and cam action to be presently described. The yoke 3 is preferably made separate from the frame 1, being bolted thereto by one or more bolts 6 as shown in Figs. 1 and 2.

The cylinder 2 contains a piston 7 and is closed at its rear end by a head casting 8 which also provides a guide and support for a piston rod 9 connected at its forward end to the piston 7 as shown. The rod 9 extends slidably through the head 8 into an auxiliary cylinder 10, the latter

being secured to and closed at its forward end by said head casting 8.

The cylinder 10 is smaller in diameter than the main cylinder 2 and contains a piston 11 connected to the rear end of the rod 9. The rod 9 is provided with a pressure fluid passage 12 which opens into the cylinder 10 through the rear end of the rod and connects adjacent its front end with the cylinder 2 through a port 13 in the rod on the rear side of the piston 7 as shown. By this arrangement, pressure fluid supplied to the main cylinder 2 will enter the auxiliary cylinder 10 and act simultaneously on the pistons in both cylinders to drive the pistons forwardly on a power stroke. The flow of pressure fluid to the cylinders is controlled by a manually operable throttle valve carried by the head casting 8 between the cylinders 2 and 10 and which valve is detailed in Figs. 10 and 11 and will be later described. It is sufficient to say at this point that when the valve device is positioned as shown in Figs. 10 and 14, the pressure fluid drives both pistons forwardly on a power stroke. On the other hand, when the valve device is positioned as shown in Figs. 11 and 15, the pressure fluid enters the auxiliary cylinder 10 on the front side of its piston 11 and returns both pistons to the beginning of the power stroke.

The lever and cam mechanism which transmits the power of the pistons to the plunger or ram 5 and multiplies the power to that required for a cold riveting operation is located in a housing 14 provided by the frame or support 1 in advance of its connection with the cylinder 2. The power lever 15 of this mechanism is fulcrumed at its upper end in said housing 14 on a fulcrum pin 16. The latter is mounted at its ends in the side walls 17, 18 of the housing 14 and allows the lower end of said lever to be swung towards and from the plunger 5. A link 19 connects the lower or swingable end of the lever 15 to a pair of links 20, 20 which project forwardly from the piston 7. A pivot pin 21 provides the connection between the link 19 and the lever 15, the latter having a forwardly extending portion 22 to engage the inner end 23 of the plunger or ram 5. The inner end 23 of the plunger is enlarged to provide a seat for a coiled spring 24 which keeps the plunger 5 in contact with the lever 15 and causes the plunger to follow the lever on the return stroke of the pistons 7 and 11.

The links 20, 20 are pivotally connected to the piston 7 through a pair of forwardly projecting apertured lugs 25, 25 on the piston and a cooperating pivot rod 26. The latter extends through the lugs and the links and is held from rotation by a screw 27 which extends through the rod and is screwed into the adjacent end of the piston rod 9 at its clamp nut 28. The latter is screwed on the forward end of the piston rod 9 to clamp the piston 7 thereto as shown in Figs. 1 and 2.

The rod 26 provides a rotatable mounting for the links 20, 20, the latter being parallel and connected at their forward ends to the lever 19 by a cross-pin 29. Said cross-pin 29 has its ends journaled in the links 20 and carries between them a roller 30 which co-acts with a cam-shaped track-way 31 fixed in the housing 14 above the links as shown. The links 20 are held in their assembled relation by a combined fastening and spacer element. The latter comprises a spacer member 32 fitting between the links and screw elements 33 which extend into and engage the spacer member through the links as shown.

The cam-track 31 is on the under-side of a cam-block 34 which is secured in the housing 14 above the roller 30 by a screw and dowel arrangement shown in Fig. 1. The screw is marked 35 and the dowels are marked 36.

The operation of the machine so far described is as follows: The piston 7 is brought to the beginning of its power stroke by admitting pressure fluid into the auxiliary cylinder 10 on the forward side of its piston 11. This brings the piston 7 adjacent to the head 8 and shifts the roller 30 to the start or low point a (Fig. 13) of the cam-track. The lever 15 is swung rearwardly about its fulcrum 16 and reaches the position shown at B in Fig. 13. The link 19 occupies the position shown at C and the plunger 5 due to its spring 24 follows the lever to the position shown at D. It may be remarked at this point that the spring 24 also holds the roller 30 against the cam-track 31. Pressure fluid is now admitted to the rear end of the cylinder 2 through the throttle valve heretofore referred to and both pistons are driven forwardly. This moves the roller 30 forwardly along the cam-track 31, the curvature or shape of which is designed to progressively diminish the unit of arcuate movement of the lever 15 towards the plunger 5 and thus greatly increase the power on the plunger. This increase in power will be apparent from an inspection of Fig. 13.

The left hand group of numerals 1 to 6 inclusive in Fig. 13 represent equal divisions of the power stroke of the pistons from E to E'. The right hand group of numerals 1 to 6 inclusive 35 show the extent of the arcuate movement given to the lever 15 for each corresponding unit of movement 1 to 6 of the pistons. It will be noted that the units of arcuate movement of the lever 15 decrease rapidly in the power stroke of the 40 pistons and thus cause the lever 15 to build-up a considerable pressure on the plunger 5 as the roller 30 travels along the cam-track 31 from its low point a to its high point b. This shortening of the throw of the lever 15 as compared 45 to the stroke of the pistons 7 and 11 is brought about by the change in angularity between the lever 15 and the link 19 due to the curvature of the cam-track 31. Hence, the ratio per unit 50 of movement of the lever 15 and the pistons increases on the power stroke of the pistons and considerable power is available for the riveting stroke of the plunger. In the particular embodiment shown, it is possible with a one-half inch travel for the plunger to obtain an ultimate pressure at the plunger of a ratio of more than 8 to 1 over the pressure due to the areas of the pistons and the pressure in the supply line.

It will be noted that the first units of the travel 60 of the lever 15 is of a greater extent than the remaining units of movement. This causes the lever 15 to move faster in the initial travel of the roller 30 along the track-way 31 and hence the plunger 5 is brought quickly against the rivet to be operated upon. The remainder of the travel 65 of the lever is progressively less per unit of movement and considerable pressure is exerted on the plunger through the lever per unit of travel of the pistons. With both pistons under pressure, more power is available than should only one piston be relied upon. As further evidence of the increased power developed by the machine, attention is called to the ratio of travel of the pistons and the plunger, respectively. In Fig. 13 this ratio is about 4 to 1. In practice, the machine has sufficient power to properly

rivet and clamp on each power stroke of the pistons, thus allowing the tool to be moved rapidly from one riveting operating to another in the use of the tool.

In the machine shown, all of the load is carried at the points F, G, which points are at the cam-block 34 and fulcrum pin 16, respectively. With a heavy cam-block and a heavy fulcrum pin, both securely anchored in the frame 1, no strains are transmitted to the pistons. The power load is carried by the lever 15 and the link 19. These parts are heavy one-piece solid elements and thus adequately take the power strains.

As shown in Fig. 3, the link 19 is bifurcated at its opposite ends to straddle the lever 15 and the roller 30, respectively. At the roller, the link 19 has relatively heavy extensions 31, 31 which closely fit against the sides of the cam-block 34 to prevent lateral or side play of the parts. These extensions, as shown in Fig. 1, are arcuate in shape to retain contact with the sides of the cam-block in the swinging motion of the link 19.

The roller 30 is mounted on bearing rollers 38, 38 for ease in operation and to reduce friction. As shown in Fig. 3, the cage elements 39, 39 for the bearing rollers embrace the sides of the roller 30. The latter is as wide as the cam-block 34 to insure full pressure contact of the roller 30 with the cam-track 31.

As shown in Fig. 2, the lugs 25 are integral with the piston 7 and the latter has cylindrical recesses 40 at the outer sides of the lugs and in line with the bores thereof so that the pivot bar 26 may be readily inserted into and be withdrawn from the lugs in assembling and disassembling the machine. Also, the lugs 25 are spaced apart to provide a recess for the clamp nut 28 and the holding screw 27.

The pistons 7 and 11 are each equipped with replaceable leather cup packings 41, 42, respectively, to engage the inner walls of their associated cylinders 2 and 10. The auxiliary cylinder 10 is preferably made in one piece as shown and has a threaded connection with the head casting 8. A threaded ring 43 is employed to clamp the cylinder 10 to the head 8, as depicted in Figs. 1 and 2. By this arrangement, the auxiliary cylinder 10 may be easily removed for inspection or adjustment.

Also, as shown in Figs. 1 and 2, a bearing bushing 44 is fitted in the head 8 for the piston rod 9. The power cylinder 2 is secured at its ends to the frame 1 and the head 8, respectively, in any desired manner. Screw bolts and lugs on the respective parts may be employed for these connections as in portable tool design. The frame 1 is constructed to take standard yokes. In this connection, it is pointed out that the frame has a forwardly projecting integral web portion 45 to which the yoke is secured by the bolts 6, the yoke being bifurcated as at 46 to straddle the web as shown.

The mounting for the plunger 5 is releasable so that plungers may be quickly and easily removed for changing. In the embodiment shown, the plunger 5 is reciprocable in a housing 47 which is insertible into a channel-way 48 provided in the underside of the frame 1 forwardly of the lever 15. The complementary flat side walls 49, 50 of the housing 47 and the channel 48 fit against each other when the parts are assembled as shown in Figs. 4 to 6 inclusive. The housing 47 carries a tail piece 51 which projects rearwardly and serves as a closure for the open lower portion of the housing 47 in the region of

the lever 15 and the inner end of the plunger 5 as shown in Fig. 1.

The housing 47 is provided in each side wall 49 with a longitudinally extending groove 52 and a number of slots 53 spaced along the groove and opening into the same from above. The grooves and the slots open laterally through the side walls of the housing and the slots also open through the upper surface 54 of said housing. 10 Riveted or otherwise fixedly secured to the side walls 50 of the channel-way 48 are key-bars 55, 55. These bars are aligned horizontally and each bar has an equal number of notches 56 which provide lugs 57 on the bars. The lugs 57 are located in the grooves 52 out of line with the slots 53 when locking the housing 47 in the channel 48 as shown in Fig. 4. To make this connection the housing 47 is first positioned below the channel 48 in substantial parallel relation thereto with slots 53 in registration with the key-lugs 57. The housing 47 is now moved bodily upward into the channel 48, the lugs 57 passing through the slots 53 and into the grooves 52. The upward movement of the housing 47 is stopped on contact of the lugs 57 with the bottoms of the grooves 52 below the slots 53, whereupon the housing 47 may move forwardly in a longitudinal direction to carry the slots 53 out of registration with the lugs 57. This locates the lugs 57 below the portions of the grooves 52 beyond the slots 53 and the housing is interlocked with the frame 1 with the plunger 5 in line with the operative end of the lever 15. It should be remarked here that the plunger 5 is placed in the bore of the housing 47 before the latter is inserted into the channel 48. Also, the spring 24 is applied to the plunger before the latter is inserted into the channel 48.

The foregoing locates the spring in its operative position between the headed inner end 23 of the plunger and the housing 47. In mounting the assembly in the frame, it is necessary to keep the housing 47 pressed back against the spring to align the slots 53 with the key-lugs 57. When these lugs reach the bottom of the grooves 52, the housing 47 is released and the spring 24 expands to move the housing forwardly to interlock the housing with the frame. This forward movement of the housing 47 is stopped by contact of the rearmost lugs 57 with the ends of the grooves 52 which are closed for this purpose. The pressure of the spring 24 keeps the housing 47 interlocked with the lugs 57 and the housing is retained in the frame with the plunger 5 in line with the lever 15.

To remove the plunger, the housing 47 is pressed back against the spring 24 until the lugs 57 register with the slots 53 whereupon the housing is free of the frame 1 and may be dropped out for replacement of its plunger. The structure described provides a readily releasable mounting for the plunger and quick changing of plungers for rivets of different lengths may be made with minimum effort. The outer or operative end of a plunger may be recessed to form a head on a rivet as understood in this art.

To adjust the stroke of the plunger 5 as when setting it to operate on shorter rivets, I provide a stop element 58. The latter is mounted in the frame 1 adjacent the rear end of the plunger 5 and is projectible into and out of the path of movement of the headed inner end 23 of said plunger. In Fig. 4, the stop 58 is shown out of the path of the plunger, being held in this position by its cross-head 59 at the upper end of the

stop spanning a kerf 60 in the outer end of the stop mounting 61. When the head 59 is turned to enter the kerf 60, the spring 62 about the stop 58 projects it inwardly into the path of the plunger 5. This is done when the plunger is pulled forwardly to position its headed inner end beyond the stop as shown in Fig. 12. When the parts are so positioned, the forward end of the plunger 5 reaches a shorter rivet and the extent of the plunger travel is accordingly shortened.

The throttle valve as detailed in Figs. 10 and 11 comprises a tubular housing 63 mounting a reciprocable valve element 64. The latter has a stem or a rod 65 to which is secured a pair of valve members 66, 67 in spaced relation. The members 66, 67 are cylindrical and slidably engage the inner cylindrical wall of the housing 63 as shown. The members 66, 67 are spaced apart axially of the rod 65, the upper member 66 controlling the admission and exhaust of pressure fluid into and out of the main cylinder 2, while the lower member 67 has a similar function for the auxiliary cylinder 10.

The main inlet port 68 in the housing 63 is located between the valve members 66, 67 and is connected to the air hose socket 69 in the head 8 through which the pressure fluid is supplied to the tool. The ports 68 and 69 are joined by an interposed passage-way 8a in the head 8 as shown in Fig. 2. The valve members 66, 67 are spaced apart a fixed distance so as not to close the inlet port 68 when opening or closing the ports for the cylinders 2 and 10.

Ports 70 and 71 in the housing 63 are connected to the main cylinder 2 on the rear side of the piston 7 through a port 72 in the head casting 8 as shown in Fig. 2. Ports 70 and 71 are opened and closed by the valve member 66. The latter is chambered as indicated at 73 to accommodate a pair of coiled springs 74, 75 and a sleeve 76 which is slidably mounted on the stem or rod 65 between the valve member 66 and a shoulder 77 on said stem. The first mentioned spring 74 encircles the sleeve 76 and is long enough to seat at its lower end against the valve member 66 at the bottom of the chamber 73, and at its upper end against a screw plug 78 which closes the upper end of the housing 63. The plug 78 also provides a bearing and guide for the valve stem 65 as shown. The other spring 75 is smaller in diameter and fits about the portion of the rod 65 between the lower end of the sleeve 76 and the bottom of the chamber 73 as shown in Figs. 10 and 11. The purpose of this spring arrangement is to move the valve device 64 downwardly when released by the operator and to offer sufficient resistance to the upward movement of the valve rod 65 to avoid a sudden starting of the machine when driving the pistons on the power stroke.

The last mentioned function is brought about by having the two inlet ports 70, 71 for the cylinder 2. The lower port 71 has a smaller area than the upper port 70 and is opened by the valve member 66 in advance of the port 70. Hence, when the valve element 64 is raised by the operator, the smaller port 71 is opened first and a smaller amount of air pressure is admitted to the cylinder 2 to start the piston 7 on the power stroke. The sleeve 76 follows upwardly with the stem 65 until stopped by contact with the plug 78. The port 70 is still closed by the valve member 66 making it necessary for the operator to compress the inner spring 75 to open the port 70 to supply the cylinder 2 with full air pressure.

The valve stem 65 is raised by a lever 79 ful-

crumed on the exterior of the head casting 8 between the cylinders 2 and 10 as shown in Fig. 1. The casting 8 has a lug 80 to mount the fulcrum. The longer arm of the lever 79 overlies the cylinder 10, the arrangement being such that the lever extends lengthwise of the cylinder as shown. The shorter arm of the lever 79 is connected to the upper end of the valve rod 65 by a pivot pin 82, the valve rod being bifurcated to accommodate the adjacent end of the lever 79.

The valve member 67 controls a pair of vertically spaced ports 83, 84 located in the housing 63 adjacent its lower end as shown in Figs. 10 and 11. The port 83 is the inlet port for the auxiliary cylinder 10, while the port 84 is the exhaust port for said cylinder. The port 83 is connected to the cylinder 10 by a passageway 8b in the head element 8 as shown in Fig. 2. The housing 63 is provided at its lower end with a port 85 which connects the bore of the housing with cross-ports 86 in the extreme lower end of the housing. The exhaust ports for the cylinder 2 in the housing 63 are marked 87, 87. These ports are above the inlet ports 70, 71 and are opened and closed by the valve member 66.

When the valve parts are in the positions shown in Fig. 11, the main inlet port 68 is connected through the bore of housing 63 with the inlet port 83 for the auxiliary cylinder 10 and fluid pressure is admitted to the forward end of said cylinder to return the pistons to the beginning of the power stroke. The exhaust ports 87 are at this time, for the main cylinder 2, uncovered by the valve member 66 and said cylinder exhausts to the atmosphere through the exhaust outlet 89 for the tool in the head element 8. The latter is provided with a passageway 8c connecting the exhaust outlet 89 with the exhaust ports 87 and 86, respectively, as indicated in Figs. 14 and 15. The cylinder 10 on the rear side of its piston also exhausts at this time through the main cylinder 2, passage-way 12 in the piston rod 9 providing the connection. The operating lever 79 is at this time in the dotted line position shown in Fig. 1, being held in that position by the springs 74, 75.

To drive the pistons forwardly the lever 79 is moved towards the cylinder 10. This raises the valve rod 65 to the position shown in Fig. 10 and the valve member 67 is raised to close the inlet port 83 and open the exhaust port 84. This relieves the pressure on the forward side of the piston 11 and closes the exhaust ports 87 before opening the inlet ports 70, 71.

The passage arrangement between the throttle valve 64 and the pistons 2 and 10 is shown in diagram in Figs. 14 and 15. The passage-ways are suitably legended in these figures so that the use of reference characters to indicate them is deemed unnecessary. Fig. 14 shows the valve 64 positioned as in Fig. 10, while Fig. 15 shows the valve positioned as in Fig. 11.

The operations above described are repeated in alternation for each riveting action. The lever 79 is released to return the plunger 5 to the beginning of its riveting stroke, whereas the lever is moved towards the cylinder 10 to drive the plunger forwardly. The lever 79 is mounted as shown to be readily accessible and operable with one hand of the operator holding the tool about the auxiliary cylinder 10. The diameter of this cylinder is made small enough to provide a hand hold for the tool. The operator grasps the tool with his other hand at the frame 4, the tool being held in the position desired to engage the work between the anvil 4 and the plunger 5.

The tool may be moved along the work from one riveting point to the next and complete a riveting action on each power stroke of the plunger.

When riveting steel or other hard metal rivets the full power of the machine will be employed. To adjust the machine to operate on softer rivets, the power factor of the machine is reduced to that required for the softer metal. This is accomplished through the medium of an adjustable relief valve shown at 90 in Fig. 2.

The valve fixture 90, in the embodiment illustrated, comprises a body member 91 screwed into the head 8 between the cylinders 2 and 10 at a duct 92 which leads to the inner end of the cylinder 2. The body member 91 has a tapered bore to accommodate a complementary shaped valve plug 93. The latter is held in seated relation within the bore of the body member 91 by a coiled spring 94 bearing at one end against the plug 93 in a recess therein and at its opposite end against a cap-member 95 which closes the outer end of the body member 91. The cap-member 95 has screw threaded connection with the body member 91 for adjustment axially to vary the tension of the spring 94 on the valve plug 93. The cap-member 95 is also provided with a number of vent openings 96 which release the pressure in the cylinder 2 when the valve element 93 is raised or moved outwardly against its spring 94. The cap 95 may be knurled or otherwise formed to facilitate turning it and any suitable graduation arrangement may be provided to indicate an adjustment for any given pressure.

It will be apparent from the foregoing that by setting or adjusting the valve member 93 to the pressure desired the machine will be operated at that pressure. This is, of course, less than the maximum pressure of the machine which pressure is available on setting the relief valve not to open.

The machine shown and described is not only simple in construction and operation, but as heretofore indicated, is relatively small in size, compact in design and light in weight. The throttle valve mechanism shown in Figs. 10 and 11 enables the operator to readily control the operation of the machine while holding it in position of use. The relief valve 90 enables the pressure factor to be adjusted as when desired and hence the machine is not limited to rivets of any given ductility. Also, the machine is adjustable for short and long rivets which factor contributes to the efficiency of the mechanism as a commercial product. In keeping with this purpose, the yoke 3 is removably secured to the frame 1 so that yokes of various designs may be employed with the machine to give it more universal use.

Another feature of importance is the provision of a slot 13a in the outer surface of the rod 9 at the port 13. This slot extends to the adjacent surface of the piston 7 and connects the passage 12 with the cylinder 2 when the port 13 is within the bushing 44 and is covered thereby. Hence, the auxiliary cylinder 10 is not cut-off from the main cylinder 2 when the piston 7 is against the bushing 44 as when at the beginning of the power stroke. The slot 13a opens into the cylinder 2 at this position of the piston 7 and the cylinder 10 is supplied with compressed air from the cylinder 2 as soon as the throttle valve 64 is actuated to connect the tool with the compressed air supply. This gives a smooth and even starting movement for the pistons because both are acted on simultaneously by the motive fluid and not one in

advance of the other which would occur should the opening of the port 13 be delayed. The outer surface of the rod 9 at the port 13 may be milled flat to aid the connection with the cylinder 2 when the piston 7 is directly against the bushing 44 or the boss which supports it.

The details of construction and arrangement of parts shown and described may be variously changed and modified without departing from the spirit and scope of my invention, except as pointed out in the annexed claims.

I claim as my invention:

1. In a riveting machine, the combination with a support, of a cam-track and a riveting plunger carried by the support, said cam-track being stationarily mounted on said support, a lever fulcrumed on the support between the cam-track and the plunger, a roller, a reciprocable power element having a straight line movement on the support with the center line of the movement parallel to the plunger and disposed between the cam-track and the fulcrum of the lever, and links connecting the roller to the power element and to the swingable end of the lever, respectively, for forcing the lever with an increasing power against the plunger in the travel of the roller along the cam-track towards the lever.

2. In a riveting machine, the combination with a support, of a cam-track and a riveting plunger mounted on the support, said cam-track being stationarily mounted on said support, a lever fulcrumed on the support between the cam-track and the plunger, a roller, power means for moving the roller along the cam-track towards the lever, pivotally connected first and second links, the first link connecting the roller to the power means and the second link connecting the roller to the swingable end of the lever for forcing the lever with an increasing power against the plunger in the movement of the roller along the cam-track towards the lever, spring means acting through the plunger for holding the plunger against the lever and the roller against the cam-track, and auxiliary power means acting through the first mentioned link for moving the roller to its starting position on the cam-track following the power stroke of the lever on the plunger.

3. In a riveting machine, the combination with a support, of a cam-track and a plunger mounted on the support, said cam-track being stationarily mounted on said support, a lever fulcrumed on the support between the cam-track and the lever, a roller, main and auxiliary pistons connected for movement in unison, links connecting the roller to the main piston and to the swingable end of the lever, respectively, for forcing the lever with an increasing power against the plunger in the movement of the roller along the cam-track towards the lever, and valve means for controlling the flow of pressure fluid to the pistons whereby both pistons may be placed under power when moving the roller towards the lever and only the auxiliary piston being placed under power when moving the roller in the opposite direction.

4. In a riveting machine, the combination with a support, of a cam-track and a riveting plunger carried by the support, said cam-track being stationarily mounted on said support, a lever fulcrumed on the support between the cam-track and the plunger, a roller, a main cylinder and an auxiliary cylinder, both carried by the support and each containing a piston, a rod joining the pistons for movement in unison and having a passage-way therein to connect the auxiliary

cylinder to the main cylinder on the same side of their respective pistons, links connecting the roller to the piston of the main cylinder and to the swingable end of the lever, respectively, for forcing the lever against the plunger in the travel of the roller along the cam-track towards the lever, and valve means for admitting pressure fluid to the main cylinder when placing both pistons under power for moving the roller towards the lever and to the auxiliary cylinder only when moving the roller in the opposite direction.

5. In a riveting machine, the combination with a support, of a riveting plunger, power means carried by the support for imparting a riveting stroke to the plunger, a housing providing a reciprocable mounting for the plunger, and interengageable means on the housing and the support, respectively, for releasably connecting the housing to the support and holding the plunger in operative relation to the power means.

6. In a riveting machine, the combination with a support, of a riveting plunger, power means carried by the support for imparting a riveting stroke to the plunger, a housing providing a reciprocable mounting for the plunger, and interengageable lugs and slots on the support and the housing, respectively, for releasably connecting the housing to the support and holding the plunger in operative relation to the power means.

7. In a riveting machine, the combination with a support, of a riveting plunger, power means carried by the support for imparting a riveting stroke to the plunger, a housing providing a reciprocable mounting for the plunger, key elements carried by the support, intersecting grooves and slots in the housing to receive the key elements for releasably connecting the housing to the support and for holding the plunger in operative relation to the power means, and spring means for holding the housing in connected relation with the key elements.

8. In a riveting machine, the combination with a support, of a cam-track and a riveting plunger carried by the support, said cam-track being stationarily mounted on said support, a lever fulcrumed on the support between the cam-track and the plunger, a roller, power means for moving the roller along the cam-track, a link connecting the roller to the swingable end of the lever for forcing the lever with an increasing power against the plunger in the travel of the roller along the cam-track towards the lever, and a stop carried by the support for adjustment into and out of the path of the plunger for controlling the stroke thereof.

9. In a riveting machine, the combination with a support, of a riveting plunger carried by the support, a power cylinder containing a piston mounted on the support, means for transmitting the power of the piston to the plunger for imparting a riveting stroke thereto, and valve

means for controlling the flow of pressure fluid to said cylinder, said valve means having a manually operable movable valve member and a number of inlet ports controlled thereby, said ports being of different sizes and arranged with the smaller port to be opened first to control the amount of pressure fluid admitted to the cylinder in the initial starting of the piston on its power stroke.

10. In a riveting machine, the combination with a support, of a riveting plunger carried by the support, a power cylinder containing a piston mounted on the support, means for transmitting the power of the piston to the plunger to impart a riveting stroke thereto, valve means for controlling the flow of pressure fluid to said cylinder, said valve means having a manually operable valve member and cooperating inlet ports of different sizes with the smaller port to be opened first to control the amount of pressure admitted to the cylinder in the initial movement of the piston on its power stroke, a main spring for normally urging the valve member to a position closing said ports, and an auxiliary spring and a co-acting abutment therefor to exert an additional resistance to the opening of the valve member following the opening of said smaller port.

11. In a riveting machine, the combination with a support, of a riveting plunger, power means for imparting a riveting stroke to the plunger, said power means having first and second cylinders both carried by the support and each containing a piston, a rod connecting the pistons for movement in unison, a tubular bearing for the rod between the pistons, valve means for admitting pressure fluid to the first cylinder, said rod having a passage-way therein opening into the second cylinder on the side of the piston facing away from the first cylinder, a port in the rod for connecting the passage-way with the first cylinder, and a slot in the rod at said port for connecting the same with the first cylinder when the port is within and covered by the bearing.

12. In a riveting machine, the combination with a support, of a riveting plunger slidably carried by said support, a cam-track stationarily mounted on the support, said cam-track extending in the same general direction as the plunger and offset wholly to one side thereof, a lever fulcrumed at one end on the support between the cam-track and the plunger and having its swingable end engageable with the plunger, a roller, power means mounted on the support for moving the roller along the cam-track, and links connecting the roller to the power means and to the swingable end of the lever, respectively, for forcing the lever with an increasing power against the plunger in the travel of the roller along the cam-track towards the plunger.
